DESIGN FOR A CLOCK CASE.

WILLIAM A. GILES, OF CHICAGO, ILLINOIS.

Design No. 2,526, dated December 11, 1866.

The Schedule referred to in these Letters Patent and making part of the same.

TO ALL WHOM IT MAY CONCERN:

Be it known that I, WILLIAM A. GILES, of Chicago, in the county of Cook, and State of Illinois, have invented and produced a new and ornamental Design for Clock Cases; and I do hereby declare and make known, that the following is a full, clear, and exact description of the same, reference being had to the accompanying photographic representation thereof, forming part of this specification.

The clock case may be constructed of any suitable material or composition, walnut-wood or imitation thereof, being preferred, having surrounding the same, as shown a vine, the whole constituting a rustic case. The circular design upon the face of the clock, below the dial, may be employed or not, as preferred, it constituting no part or parul of my invention.

What I claim and desire to secure by Letters Patent, is—

The design for a rustic clock case, consisting of a vine surrounding the face of the clock, as herein shown and described.

WM. A. GILES.
